UNITED STATES PATENT OFFICE.

HOWARD R. HUGHES, OF HOUSTON, TEXAS.

HORIZONTAL-DRILLING MACHINE.

1,285,712.

Specification of Letters Patent.

Patented Nov. 26, 1918.

Application filed December 1, 1917. Serial No. 204,983.

To all whom it may concern:

Be it known that I, HOWARD R. HUGHES, a citizen of the United States, residing at Houston, Harris county, Texas, have invented a certain new and useful Improvement in Horizontal-Drilling Machines, of which the following is a full, clear, and exact description, such as will enable others skilled in the art to which it appertains to make and use the same.

My invention relates to improvements in drilling or boring machines whereby a bore or tunnel may be drilled in a direction horizontal or substantially so in the earth, and which may also be adapted for vertical drilling. My device is designed more particularly for use in warfare for the boring of holes from one trench to a point under a distant trench or fortification of the enemy which hole will serve as a passage for explosives destined to be detonated beneath the opposing fortification. It is, of course, obvious that other uses may be made of the invention and I do not limit myself to this particular purpose.

In the practice of my invention I provide a machine for operating a rotary drill which drill is of any usual construction such as, for example, one of my patented roller drills. The drill or bit is attached to the end of a hollow drill stem which serves to transmit the rotary motion to the bit and also to furnish a passage for flushing water which is pumped through said drill stem and through passages in the bit itself, said water serving to wash out from the hole the matter cut away by the bit.

This invention pertains particularly to the construction of a machine for properly operating the drill stem, giving the same a rotary movement and also a forwardly or reverse movement longitudinally of the drill stem and for directing the bit to the desired point. One object of my invention is to provide a novel means for giving a laterally directed drill a rotary motion, and at the same time allowing for a longitudinally progressive movement of said drill.

Another object is the provision of novel

means for giving said rotating bit a progressive movement at will and for regulating the speed of such progressive movement.

Another object is to construct the operating device in such manner that the bit may be directed so as to drill a hole in a plurality of directions without interfering with the efficient operation of the said device.

Another object is to so combine the different operating parts of my invention as to produce the most effective apparatus for the purpose intended.

Other objects and advantages of my improvement will more clearly appear in the specification which follows and will be more particularly pointed out in the claims. In the drawing forming a part of this specification and in which like characters of reference refer to like parts throughout the several views:

Figure 1 is a side view of my assembled device; Fig. 2 is a top plan view thereof; Fig. 3 is a detail view partly in section showing my novel means of driving the drill stem and of regulating its longitudinal movement; Fig. 4 is a transverse section on the line 4—4 of Fig. 3, looking in the direction of the arrows; Fig. 5 is a side view showing my machine reversed for drilling in an opposite direction with a larger sized drill connected thereto.

My present invention is an improvement over the device shown in my prior Patent No. 1224930, issued to me on May 8, 1917, the improvement being in the more efficient driving mechanism for the drill stem and the means of advancing the same longitudinally as desired.

The primary use of this device being the undermining of the enemy's fortifications in warfare, it has been desirable to design the structure in separate units as far as possible in order to make the parts detachable for ready transportation by hand. Furthermore, on account of the apparatus being for use in the danger zone, each part is housed for protection as far as is convenient.

The preferred embodiment of my invention is illustrated in the drawings herewith,

wherein my machine is shown as mounted upon two supporting plates 1, 1 seated on cross pieces 2, 2. The supports for the operating mechanism comprise two opposite upright substantially U-shaped metal plates 3, 3, in which is pivotally mounted the gear-casing 4 which serves as a housing for the operating means as well as a support for the drill stem 5, as will be later explained.

10 The two supporting plates 3 are held in their opposite adjusted position by means of cross bars 30 which are of the form of longitudinal bolts with a nut at one end to clamp the two plates together. Between 15 the plates and surrounding the cross bars 30 are two separating sleeves 31 which serve to space the two plates apart in an obvious manner.

The base upon which the supports are 20 mounted is further retained in place by the longitudinal cross piece or torque bar 6, shown best in Fig. 1. This torque bar is anchored at one end in the front face of the trench in which the machine is seated 25 and at the other end is retained in rigid position by the anchoring rods 7. The similar anchoring rods 7' are also used to further retain the two supporting plates 3 as shown. The gear-casing 4, which serves as 30 a housing for the operating mechanism and a support for the drill stem, consists of two similar opposite castings 9, which are adapted to fit together along a central plane and are provided with marginal bosses 9' furnishing openings through which the fastening 35 bolts 10 are fixed, thus serving to hold the two plates in coöperating position to form a closed casing. At the center portion of each of these castings or plates 9 the housing 40 is extended laterally in the form of a sleeve 11, which is threaded interiorly and serves to retain interior sleeves 13 and 14 which form extensions thereof.

On the under side of these sleeves 11 there 45 is a slot having downwardly projected lugs 12 through which clamping bolts are adapted to be passed in order to grip sleeve 11 more firmly upon the interior bearing sleeves 13 and 14, thus making them practically integral with the housing. This means is adopted in order to provide for the disassembly of the machine for easier transportation from place to place in the trench in which it is seated.

50 The drive shaft 29 which transmits rotary movement to my drilling mechanism is journaled in the base of the housing 4 at right angles to the bearing sleeves 13 and 14. It is connected up for operation with the shaft 55 32 of an electric motor 34 by means of a clutch of ordinary construction (not shown). The said clutch is housed for protection at 35 and is operated by means of a hand lever 36. A universal joint 33 is sup-

plied in the motor shaft 32 to make un- 65 necessary the exact adjustment of the units. A second motor 34' is seated beside the motor 34 and is operatively connected to the shaft 32 by means of a noiseless sprocket chain 105 and may be used in conjunction 70 with the motor 34 where extra power is needed.

Connected with the motor for purposes of regulation through a resistance grid 37, is the controller 38. These parts of my de- 75 vice are all of them old and well known and are shown in the drawing only diagrammatically as forming no part of my invention.

The bearing sleeves 13 and 14 have their 80 inner adjacent ends upturned to form peripheral flanges 19 and 18, respectively, which flanges serve to support non-friction bearings as will be later described.

Within the bearing sleeves 14 and 13 are 85 journaled the drive sleeve 16 and the screw sleeve 17, respectively. The drive sleeve 16 is cylindrical in shape and has toward the interior end thereof a marginal outstanding flange 26. This flange serves as an attach- 90 ing means through which the said sleeve 16 is fastened to the drive gear 24, by means of a series of bolts 25, thus also making the mechanism more easily detachable and portable. Within the drive sleeve 16 is positioned the main operating sleeve 21, which is 95 threaded exteriorly as at 22.

On the exterior of the operating sleeve are provided three longitudinal slots 23, which are placed at equal distances of 100 120 degrees apart around the periphery of the said sleeve. On the interior of the drive sleeve 16 are three downwardly projecting ridges 22', which register with the slots 23 and serve to slidably connect the two sleeves. 105 Thus it will be noted that the rotation of the gear wheel 24 will turn the sleeve 16 and, through the downwardly projecting parts 22', will operate the sleeve 21, giving it a likewise rotating movement. At the 110 opposite end of the casing the screw sleeve 17 is threaded interiorly to coöperate with the main operating sleeve 21. This sleeve 17 is adapted under ordinary circumstances to turn with the operating sleeve 21 and is 115 journaled for that purpose within the outer sleeve 13, in a manner which will be later described. The gear wheel 24 is driven by means of a spiral or worm gear 28 forming a part of drive shaft 29.

120 In the preferred embodiment of my invention the forward end of the outer bearing sleeve 14 is threaded exteriorly as at 39 for connection to a short length of casing pipe 41 by means of an outer coupling 125 sleeve 40. This casing 41 is connected at its opposite end to a joint 42 which retains at its opposite side the length of casing 41'

which extends for a short distance into the wall of the trench, and serves to protect the wall of the trench and as an outlet for the flushing water which is pumped through the 5 middle of the hollow stem 5 to the bit 8 at the forward end of the same. The flushing water passes out from the drill hole through the pipe 41' to the joint 42, and downwardly through an outlet pipe 43 to the sump pit 10 44 where the disintegrated matter is allowed to settle. The casing 41' and the outlet 42 may be omitted if desired, as will be later shown.

The flushing water for this operation is 15 pumped into the rear end of the drill stem by means of a rotary pump shown diagrammatically at 45, which pumps the water from the sump pit through the inlet pipe 46 and by way of a pressure chamber 51 and 20 the flexible pipe 47 to the swivel connection 48. This swivel connection 48 surrounds an inner pipe 49 closed at its rear end as at 51' by means of a cap, and connected at its forward end by means of a conical screw 25 connection 50 to the drill stem 5. The swivel connection 48 is represented as any ordinary swivel connection between two liquid conducting pipes and no details of its structure 30 are thought to be necessary.

30 The pressure chamber 51 of the pump has connected therewith an overflow pipe or bypass 53 serving to regulate the pressure of the water in the drill stem. This pressure chamber is provided also with a gage 52 serving to indicate the amount of pressure in the pipe at all times, this gage being a valuable indicator as will be later explained.

The pump 45 is operated by means of an 40 electric motor 58 stationed alongside of said pump, said motor being provided with a drive pulley 57 which is connected to the drive pulley 56 of the pump by means of a belt 54.

The gear casing 4 is pivoted in the 45 supports 3 at its lower side as shown in Figs. 3 and 4. At each side of the casing, and integral therewith, is a laterally extending journal 101, which is seated in the bearing 100 of the support for rotative movement.

50 In the upper part of each of the two supporting members 3 is an arc shaped slot 59, through which project two laterally extending pins from the casing 4, each of said pins being provided with a head 60 consisting of a threaded nut adapted to be tightened against the plate and retain the casing in adjusted position. It will be here noted that the ordinary position of the drill stem is an approximately horizontal one, but 55 that the drill may be set at various angles and in case a well is required to be dug downwardly for a short distance for the purpose of obtaining water, the machine must be assembled with the casing tipped

over to one side in a lateral position about 65 the axis of a shaft 29 so that the drill stem will point straight downward. It is apparent from Fig. 3 that this must be done before the machine is completely assembled 70 in order to avoid the contact of the drill stem with the cross piece 1 and the cross rod 30 which connects the two plates together. In fact, it is found necessary to entirely omit these two connecting members in this adjustment of the drill. 75

The gear-casing 4, as previously stated, is journaled for rotative movement about the axis of the shaft 29. Lateral extensions 101 on each side of the casing form journals which are seated in bearings 100 in the 80 supports 3. Each journal is divided into two parts like the rest of the casing 4, the parts being separable and destined to be clamped together along a central line.

Journaled axially within this casing bearing 85 is the operating shaft 29. At each side of the central screw of the gear 28 and spaced therefrom is a collar 84 or 85 integral with the shaft 29. This collar bears against a Timken non-friction bearing 90 shown inclosed in housings 82 and 83, said bearings serving as a support for the shaft 29 and also to take up any end thrust of the same. The bearing is held in adjusted position against the collar 85 by means of a 95 spacing sleeve 86 which is threaded exteriorly to receive a washer or plate 89, which serves to close the end of the casing around the bearing. This plate 89 is fixed in position by means of set bolts. To allow the 100 sleeve 86 to be rotated to tighten the bearing 82 against the collar 85 to take up any wear that may occur, a wrench may be inserted in holes provided for same around the shaft 29, as shown at 86'. A packing ring 87 and a 105 retaining nut 88 therefor are provided around the shaft 29 to prevent the escape of the lubricating oil with which the interior of the casing is to be partially filled. On the end of the shaft 29 opposite the motor 110 the bearing in the support 3 is inclosed by a plate 103 to seal that end of the bearing.

The provision for rotating the operating sleeve 21 has already been described. It now remains to show how the drill stem is given 115 its rotating and longitudinal movement through means of the operating sleeve. The operative connection between the operating sleeve and the drill stem is provided toward the rear of the drill stem which is provided 120 with a chuck or outer removable clamping block 62 attached thereto. This chuck 62 has on the side adjacent the machine itself a dental clutch coacting with a slidible clutch ring 63. This ring has projecting 125 ridges on its inner surface fitting into the grooves 23 of the operating sleeve, and is hense rotatable therewith but as it is not

4
 interiorly threaded it will slide thereon. Thus when the operating sleeve is rotated in the proper direction (a clockwise movement looking toward the front of the machine) it will grip the chuck 62 and, through it, will rotate the drill stem 5. When rotated in the opposite direction, however, the clutch ring 63 will tend to be thrown out of gear unless held manually in its coöperative position. When thus out of gear the rotation of the operating sleeve will not affect the drill stem, as the end of said sleeve is provided with an outstanding integral flange fitting rotatively within an annular groove on the inner periphery of said chuck as is usual in such structures. Thus the advance of the operating sleeve longitudinally will carry with it the chuck and hence the drill stem, but the rotative movement of the said sleeve does not affect the drill stem except through the clutch 63.

When it is desired to move the drill stem forwardly or backwardly it is accomplished through means of the screw-sleeve 17 previously described. This sleeve is in threaded connection around the operating sleeve 21. As the screw sleeve 17 is intended to normally rotate with the operating sleeve, a provision is made to increase the friction between them to accomplish this end.

This means consists of a nut composed of two parts 68 semi-circular in shape but not touching along a median line 68'. These parts 68 are each provided with a pin 72 threaded therein at points diametrically opposite each other in relation to the operating sleeve. Each pin 72 has a smooth head projecting freely within an outer ring or sleeve 69. This ring has opposite bosses 71 at the outer end thereof provided with openings to receive the pins 72. Above each pin is fitted a split locking washer 73 held in contact with the pin 72 by means of a set screw 74 threaded within the opening in said boss. When the friction is to be increased between the sleeve 69 and the operating sleeve 21, the set screw 74 is screwed down on the washer 73 thus pressing it down upon the head of the pin 72. This is done on both of the opposite set screws 74 and the two sections of the two part nut are clamped to the operating sleeve to an extent sufficient to assure their turning together under ordinary conditions yet allowing them to slip 55 when a brake is applied to the screw sleeve 17 as will be described.

The ring 69 receives the two part nut 68 in its outer fact but is shouldered somewhat against it on the inner part and this inner 60 part is keyed to the sleeve 17 so that a rotation of the ring 69 will also rotate the sleeve 17. On the inner face of the ring an inner peripheral recess receives the adjacent end of the outer sleeve 18. The inner end is also

provided with a hand wheel 70 the rotation 65 of which will also rotate the screw sleeve 17 as will be obvious.

The screw sleeve has on its inner end adjacent the sleeve 16 an outwardly extending flange 64. The outer end of said flange is 70 extended laterally away from the adjacent gear wheel 24 to form a drum 65 encircling the screw sleeve. A brake band 66 surrounds this drum and between the brake band and the drum is interposed a band 67 75 of tough flexible material of any ordinary construction for a brake lining.

As will be noted, particularly in Fig. 4 the opposite ends of the brake band and lining do not meet at the top of the drum leaving a short space for tightening the brake.

To operate the brake, each end thereof is provided with an outstanding lug 55 having a slight V-shaped recess on the outer side thereof. Operating through the casing 4 by means of a screw connection therewith are two opposite adjusting screws 78 and 80. The screw 80 has a head 77 within the casing in contact with the recess in the lug 55. This head has a wedge shaped face 90 fitting within the V-shaped recess of the brake band. The connection between the screw 80 and the head 77 is a swivel one by which the rotation of the screw will not rotate the head but will serve simply to adjust 95 its position. At its outer end, without the casing, screw 80 is provided with an angled head 81 adapted to be gripped by a wrench. The opposite screw 78 has a similar inner head 79 but the outer end is extended as at 100 76 and is provided with a hand wheel 82. It will thus be obvious that when the adjusting screw 80 has been tightened somewhat, the operation of the screw 78 by means of the hand wheel 82 will tighten or loosen the 105 brake band at will by compressing the two lugs 55 of said band toward each other. Thus the tension on the brake may be regulated to overcome the friction of the end ring 69 and cause the sleeve 17 to be held 110 stationary. In such stationary position the continued rotation of the operating sleeve 21 will act through the screw connection between the two sleeves 17 and 21 to advance or reverse the operating sleeve in a longitudinal direction. It will also be noted that a degree of pressure may be regulated on the brake band at will which will cause the screw sleeve 17 to be rotated at a slower 115 speed than that of the operating sleeve by allowing an amount of slippage of the brake band on the drum as desired.

In other words, if the pressure of the brake band on the drum is only slightly greater than the pressure of the friction sleeve 69 the screw sleeve may be adjusted to rotate only partially in relation to the operating sleeve 21. 120

Within the casing 4 and between the dif-

ferent rotating parts, as between the flange 19 of sleeve 13 and the flange 64 of sleeve 17; between the flange 64 and the gear flange 26; between the latter and flange 18 5 of sleeve 14 are provided non-friction bearings to facilitate the movement of the operating parts.

It is contemplated that the casing 4 will be filled with lubricant to a point just below 10 the operating sleeve. An opening 90 is provided at the upper part of said casing for the purpose of supplying this lubricant and a like opening 91 in the base of the same serves as an exit for the oil when desired. 15 Both openings 90 and 91 are adapted to be closed by a threaded plug, not shown.

The drill may be reversed by the reversing of the motor itself. The reversing of the direction of rotation will throw out the 20 clutch 63 automatically thus leaving the drill stem non-rotatable. By tightening the brake band the reverse rotation of the operating sleeve 21 will withdraw the drill stem from the hole in a manner which will now be 25 clear.

When it is desired to drill in a direction opposite to the first position shown in Figs. 1 and 2, the drill is detached from the drill stem, the motor is then reversed and the 30 brake applied thus unscrewing the operating sleeve out of the rear of the machine until it is entirely clear of the same. The water connections are uncoupled and the operating sleeve and attached drill stem are then 35 carried around to the opposite side of the machine and screwed back into the screw sleeve in reversed direction. The drill is again attached to the stem and the water connections from the pump again made and 40 the device is then ready for operation on the opposite side of the bank as shown in Fig. 5.

When the drill is operating in either direction, it will be necessary frequently to add new lengths of pipe to the drill stem to 45 increase its length. This is done by unscrewing the screw connection 50 from the rear end of the drill stem 5 and screwing thereto another length of pipe after which the screw connection 50 is again secured 50 into the rear end of the new section and the position of the operating sleeve set back by means of the hand wheel 70 to its farthest rearward position. The chuck is then also readjusted on the drill stem and the operation 55 proceeds as before.

Fig. 5 illustrates how the new lengths of drill stem may be fed in as desired at the forward end of the machine. In this method the stem is uncoupled as at 104 and 60 a new length fitted therein, the rear end of the stem being drawn back after uncoupling a sufficient distance for this purpose. For convenience in this process of inserting lengths of the drill stem, the outer casing

40, 41 and the outlet joint 42 and pipe 43 65 have been dispensed with and the flushing water issuing from the drill hole is caught in a trough 106 which carries it to the sump.

When it is desired to use a larger drill and a larger drill stem in the bore hole in 70 order to get an increased size of hole, this is done as illustrated in Fig. 5. Here the usual size of drill stem 5 at the machine, within the operating sleeve, is retained but an enlarged coupling 104 is screwed thereon, 75 one end of said coupling being of the proper size therefor. In the opposite enlarged end of said coupling is screwed the enlarged size of drill stem 5' necessary to accommodate the larger drill. It is practically necessary, in the use of the enlarged size of 80 drill stem, that the new lengths be inserted from the front of the machine, as shown in this figure.

In the ordinary use of my device the different units of my apparatus are adapted to 85 be transported separately from place to place by hand. A somewhat widened placement is dug in the trench and the base plates 2 laid down and the device assembled thereon in a manner which will be clear from the 90 drawings without further description.

When assembled, the universal clutch 33 in the motor drive shaft allows for any unequal alinement of the motor and the boring 95 machine so that no delay may be necessary for exact placement of the units. The controller is operated, and when the motor is properly regulated, the clutch lever 36 is used to throw the operating mechanism into 100 gear.

The rotation of shaft 29 is transmitted through the worm gear 28, 26 to the sleeve 16 and through it to the operating sleeve 21. The rotation of the operating sleeve 21 is 105 transmitted through the clutch 63 to the chuck 62 on the drill stem and thus the bit 8 at the forward end of the drill stem is rotated.

During the rotation of the drill the screw 110 sleeve is adjusted to normally rotate with the operating sleeve through the friction ring 69 as previously described, and in such condition there is no forward movement of the drill. But when the brake band is tightened sufficiently the sleeve 17 is held against 115 rotation, or partially so as desired. When thus held, it is obvious that the operating sleeve will be advanced and hence with it the drill stem and bit. If at any time it is 120 desired to advance or withdraw the bit without the use of the brake, it may be manually accomplished by the use of the hand wheel 70 which, as described, is keyed to the screw sleeve 17.

During the operation of the bit, the pump is also operated to force the flushing water through the hollow drill stem to the bit

where the water serves to wash away the detritus. The muck laden water returns outside of the drill stem to the joint 42 where it makes its exit through the pipe 43 to the 5 sump 44.

The intake pipe 46 is provided with a straining means at the lower end and in practice, the water is used over again repeatedly. The pressure gage 52 on the 10 pump serves to indicate the pressure of water in the pipe and will show the condition of things in the pipe. Thus if the drill hole becomes clogged the rise in pressure would indicate it. If the drill stem becomes broken, a sudden falling off of the 15 pressure would bring the fact to the attention of the driller.

It is clear from what is shown that the 20 position of the drill stem need not be exactly horizontal but that adjustment of the drill hole along a vertical plane may be easily made. A level 61 on the casing is provided to determine the angle of adjustment in the direction of the bore hole.

Having thus described my invention, 25 what I claim as new and desire to protect by Letters Patent is:

1. In a device of the character described, a support, a casing, a horizontal drive shaft 30 journaled in said casing, said casing being adapted to rock about said shaft in said support, an operating sleeve, a drill inside said operating sleeve, connecting gears between said drive shaft and said operating sleeve 35 whereby the drill stem is rotated, a screw sleeve on said operating sleeve and means on said screw sleeve, and operable through the rotation of said operating sleeve, to feed the said operating sleeve forward as de- 40 sired.

2. In a device of the character described, a casing, a horizontal drive shaft journaled in said casing, an operating sleeve in said casing above and at right angles to said 45 shaft, a drill stem in said sleeve, said casing being adapted to rock about said shaft, connecting gears between said shaft and said operating sleeve, a screw sleeve on said operating sleeve and means including a 50 brake connected therewith and operable through the rotation of said operating sleeve to feed the said operating sleeve and drill stem forward at the speed desired.

3. A device of the character described 55 comprising a drill stem mounted to rock on a horizontal shaft at right angles thereto, operating means between said shaft and said stem; including an exteriorly threaded operating sleeve surrounding said stem, a 60 screw sleeve on said operating sleeve free to rotate therewith, a brake band on said screw sleeve, and means to tighten said brake band to regulate the speed of rotation of said screw sleeve.

4. A device of the character described 65 comprising a motor, a drive shaft operated thereby and detachable therefrom, a hollow drill stem operably connected with said drive shaft, and adapted to rock about said drive shaft at right angles thereto, a pump 70 operated by means detached from said shaft and adapted to pump fluid through said drill stem.

5. In a device of the character described 75 a drill, an approximately horizontal drill stem, a screw sleeve, threaded means between said drill stem and said screw sleeve, adjustable means to cause said screw sleeve to normally rotate with said drill stem; a brake to operably connect said screw sleeve 80 and said threaded means to advance said drill and means to operate said drill stem.

6. In a device of the character described 85 an operating sleeve, means to rotate said sleeve, an outer coöperating screw sleeve, friction means to cause the screw sleeve to normally rotate with said operating sleeve, and a brake on said screw sleeve to regulate the relative rotation between said screw 90 sleeve and operating sleeve.

7. In a device of the character described 95 a drive shaft, a drill stem, operating means between said drill stem and said drive shaft comprising a worm gear, a drive sleeve, a slotted operating sleeve between said drive sleeve and said drill stem capable of being reversed in position in said drive sleeve to drill in an opposite direction.

8. In a device of the character described, 100 a drive shaft, a drill stem, operating means between said drive shaft and said drill stem comprising an operating sleeve detachably connected to said stem, said operating sleeve being removable and reversible end for end without removing the drill stem 105 therefrom.

9. In a device of the character described, 110 a drive shaft, a drill stem, operating means between said drive shaft and said drill stem, comprising an operating sleeve attached to said drill stem, said operating sleeve being removable and reversible end for end without removing the drill stem therefrom, and means connected to said sleeve for feeding it forward at the desired speed. 115

10. In a device of the character described, 120 a drive shaft, an operating sleeve, operating means between said shaft and said sleeve, a drill stem within said sleeve, a screw sleeve threaded exteriorly on said operating sleeve, a spring pressed split ring between said operating sleeve and said screw sleeve to cause them to normally rotate together, and friction means to adjust the rate of rotation of said screw sleeve. 125

11. In a device of the kind described, an operating sleeve, means to rotate said sleeve, an outer coöperating screw sleeve, friction

means to cause said screw sleeve to normally rotate with said operating sleeve comprising a split ring, springs holding said ring in adjustable contact with said operating sleeve, and connecting means between said ring and said screw sleeve.

12. In a device of the character described, a horizontal drive shaft, an operating sleeve geared to said drive shaft and adapted to rock vertically on said shaft, a drill stem

in said sleeve, a screw sleeve threaded on said operating sleeve, and friction means normally holding said screw sleeve in rotation with said operating sleeve and a brake to cause said screw sleeve to rotate at a different speed than said operating sleeve.

In testimony whereof, I hereunto affix my signature this the 26th day of November, 1917.

HOWARD R. HUGHES.
